(57) **CLAIM**

The ornamental design for a vehicle wheel, toy vehicle wheel, and/or replicas thereof, as shown and described.

DESCRIPTION

FIG. 1 is a front perspective view of a vehicle wheel, toy vehicle wheel, and/or replicas thereof embodying my new design;

FIG. 2 is a front and side perspective view thereof;

FIG. 3 is a side perspective view thereof;

FIG. 4 is a front elevation view thereof;

FIG. 5 is a rear elevation view thereof; and,

FIG. 6 is a side elevation view thereof.

The ghosted or low contrasted showing of the vehicle wheel, toy vehicle wheel, and/or replicas thereof is provided for the purposes of illustrating environmental structure that form no part of the claimed design.

1 Claim, 6 Drawing Sheets
